Primary Examiner — Marianne Pandozzi*Assistant Examiner* — Jae Liang(74) *Attorney, Agent, or Firm* — Olson & Cepuritis, Ltd.(57) **CLAIM**

The ornamental design for a straw transitions cup, as shown and described.

DESCRIPTION

FIG. 1 is a perspective view of a straw transition cup showing our new design;

FIG. 2 is a front elevational view of the straw transition cup shown in FIG. 1;

FIG. 3 is a rear elevational view of the straw transition cup shown in FIG. 1;

FIG. 4 is a right side elevational view of the straw transition cup shown in FIG. 1; the left side elevational view being a mirror image thereof;

FIG. 5 is a top plan view of the straw transition cup shown in FIG. 1;

FIG. 6 is a bottom plan view of the straw transition cup shown in FIG. 1; and,

FIG. 7 is a perspective view of the straw transition cup shown in FIG. 1, with a straw extended.

The broken lines in the drawing depict portions of the straw transition cup that form no part of the claimed design.
